UNITED STATES PATENT OFFICE.

CHARLES W. ALLEN, OF PHILADELPHIA, PENNSYLVANIA.

FASTENER FOR ENVELOPS.

SPECIFICATION forming part of Letters Patent No. 729,832, dated June 2, 1903.

Application filed November 4, 1902. Serial No. 130,030. (Model.)

To all whom it may concern:

Be it known that I, CHARLES W. ALLEN, a citizen of Great Britain, residing at Philadelphia, Pennsylvania, have invented certain new and useful Improvements in Fasteners for Envelops, of which the following is a specification.

This invention relates to a fastener for envelops, bags, and similar articles which effectively protects their contents against pilfering and is not apt to become broken or injured during handling or by high temperature.

In the accompanying drawings, Figure 1 is a front view of an envelop provided with my improved fastener; Fig. 2, a plan of the shell with the string knotted; Fig. 3, a cross-section of Fig. 2; Fig. 4, a plan of the cap; Fig. 5, a perspective view of the same; Fig. 6, a cross - section of cap and shell assembled, showing them before being compressed; Fig. 7, a plan of the same after being compressed; Fig. 8, a perspective view of a modification of the cap; and Fig. 9 a plan thereof, showing it in connection with the shell.

My improved fastener is composed, essentially, of two parts, an outer shell and an inner cap which is adapted to fit the shell and to become interlocked therewith.

The shell *a* consists of a plate of rigid material provided with an inwardly-inclined circumferential side wall *a'*. This side wall is preferably denticulated, and each tooth may be mutilated by a short transverse incision

*a*² or otherwise. The body of shell *a* is provided with a pair of perforations *a*³ for admitting the two ends of a string or equivalent device *b*, which may be thus interknotted above the shell.

The cap *c* is composed of a plain bottom and a corrugated flaring wall *c'*, which inclines in the same general direction as the wall *a'* of shell *a*. The wall *c'* is expansible under pressure and is to this effect shown to be provided with longitudinal flutes or corrugations, Figs. 4 and 5. When the cap is subjected to pressure, its diameter will increase, because its side wall will then be

brought into greater parallelism with the body of the cap. Suitable initials or marks 50 may be stamped upon the cap, as indicated by letters A. B.

The relative size of cap and shell is such that the wall of the former fits within the wall of the latter and that the cap is somewhat higher than the shell.

In use the string *b* is stitched through the envelop, bag, &c., and its ends are then brought forward through the holes *a*³ to be interknotted above the face of shell *a*. The 60 cap is placed upon the shell to cover the knot, Fig. 6, and pressure is applied by means of a suitable plunger. This pressure acting first upon the protruding portion of the cap will cause a preliminary flattening of the wall *c'*, 65 which will thus creep underneath wall *a'*, so as to interlock the cap with the shell. The pressure being continued, both walls will become flattened out and the entire fastener will assume the form of a hollow flat disk, 70 within which the knot is securely confined.

It will be seen that my fastener effectively secures the envelop against unauthorized opening. The security is augmented by the teeth of wall *a'*, which prevent any cutting 75 around the inner edge of the wall and which expose by their mutilation *a*² any attempt to be turned upward.

In Figs. 8 and 9 the wall *c'* of cap *c* is shown to be made expansible by means of slits *c*² in 80 lieu of the corrugations shown in Figs. 4 and 5.

It is obvious that in lieu of forming the openings in the shell they may be formed in the cap, which would be an equivalent construction.

What I claim is—

1. A fastener for envelops composed of a shell having a perforated body and a flaring side wall, an inclosed cap having a corrugated flaring expansible side wall that inclines in the same direction as the shell-wall, and a string that engages the perforated body and is knotted between shell and cap, substantially as specified.

2. In a fastener for envelops, a shell com-

posed of a perforated body and a flaring side wall having mutilated teeth, combined with an inclosed cap having a flaring expansible side wall that inclines in the same direction 5 as the shell-wall, and a string that engages the perforated body and is knotted between shell and cap, substantially as specified.

Signed by me at Philadelphia, Pennsylvania, this 1st day of November, 1902.

CHARLES W. ALLEN.
